UNITED STATES PATENT OFFICE

144,332

DESIGN FOR A WHEELED TOY

Emile L. Willemain, Holyoke, Mass., and Walter W. Morris, Hazardville, Conn.

Application September 7, 1945, Serial No. 121,907

Term of patent 3½ years

(Cl. D34—15)

To all whom it may concern:

Be it known that we, Emile L. Willemain and Walter W. Morris, citizens of the United States of America, residing, respectively, at Holyoke, in the county of Hampden and Commonwealth of Massachusetts, and Hazardville, in the county of Hartford and State of Connecticut, have invented a new, original, and ornamental Design for a Wheeled Toy, of which the following is a specification, reference being had to the accompanying drawing, forming part thereof:

Fig. 1 is a side elevational view of a wheeled toy showing our new design; and

Fig. 2 is an end elevational view of the wheeled toy shown in Fig. 1.

We claim:

The ornamental design for a wheeled toy, as shown.

EMILE L. WILLEMAIN.

WALTER W. MORRIS.
